US00D868604S

(12) **United States Design Patent** (10) Patent No.: **US D868,604 S**
 Sanroma et al. (45) Date of Patent: ** Dec. 3, 2019

(54) **SENSOR**

(71) Applicant: **General Electric Company**, Schenectady, NY (US)
 (72) Inventors: **John Paul Sanroma**, Billerica, MA (US); **Mariah Inez Hake**, Lakewood, CO (US)

(73) Assignee: **General Electric Company**, Schenectady, NY (US)

(**) Term: **15 Years**

(21) Appl. No.: **29/558,581**

(22) Filed: **Mar. 18, 2016**

(51) LOC (12) Cl. **10-04**

(52) U.S. Cl.

USPC **D10/56**; D10/52

(58) **Field of Classification Search**

USPC D10/46, 78, 101, 103, 114.6; D13/101; D14/299

CPC G01N 15/0205; G01N 21/47; G01N 21/64; G01N 21/85; G01N 25/00; G01N

2021/6417; G01N 33/00; G01N 33/1833

(57)

CLAIM

The ornamental design for a sensor, as shown and described.

DESCRIPTION

FIG. 1 is a perspective view thereof;

FIG. 2 is a front elevational view thereof;

FIG. 3 is a right side elevational view thereof;

FIG. 4 is a left side elevational view thereof; and,

FIG. 5 is back elevational view thereof.

The broken lines show portions of a sensor that form no part of the claimed design.

1 Claim, 5 Drawing Sheets
